(57) **CLAIM**

The ornamental design for a utility knife, as shown and described.

DESCRIPTION

FIG. 1 is a right side perspective view of the utility knife of the present invention showing my new design in an unfolded position;

FIG. 2 is a left side perspective view thereof;

FIG. 3 is a top plan view thereof;

FIG. 4 is bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a right side perspective view thereof, wherein the blade holder is in a half folded position; and,

FIG. 10 is a right side perspective view thereof, wherein the blade holder is in a fully folded position.

The broken line showing of the removable blade is included for the purpose of illustrating environmental structure and forms no part of the claimed design.
